UNITED STATES PATENT OFFICE.

LESLIE F. PORTER, OF PASSAIC, NEW JERSEY, ASSIGNOR TO BELL TELEPHONE LABORATORIES, INCORPORATED, OF NEW YORK, N. Y., A CORPORATION OF NEW YORK.

TELEPHONE SYSTEM.

Application filed May 25, 1927. Serial No. 194,014.

This invention relates to telephone systems and particularly to toll switching systems wherein cord circuits each comprising under normal conditions a clear pair of conductors are employed to establish connections over toll switching trunks each including a train of automatic switches.

In accordance with one feature of the invention discriminating means is provided 10 in a common dialing circuit responsive to conditions found in different character trunk lines for automatically adapting the said common dialing circuit to the particular trunk line in use. Heretofore, as shown 15 for example in Patent No. 1,567,256, to Fowler, a dialing circuit has been provided which may be automatically adapted to different character trunk lines. The present invention, however, deals with a different 20 character cord circuit in which it is necessary to maintain a clear pair of conductors for a talking circuit. Since supervisory means can not be placed in association with the talking circuit, it is necessary to use 25 the sleeve circuit for performing the supervisory functions. Therefore, discriminating means has been placed in the dialing circuit itself. The present invention, therefore, differentiates from systems such as that 30 shown in the patent to Fowler in two respects: one, the discriminating means for automatically adapting the dialing circuit to different trunk line conditions is placed in the dialing circuit itself; and, second, 35 this discriminating means has been made common to the cord circuit.

In accordance with another feature of this invention a means is provided for automatically applying ringing current to a 40 trunk line for a single period of time of predetermined duration. Schemes of this nature comprising a time counting arrangement individual to the trunks have been used heretofore, so that the present feature is in the nature of an improvement 45 over such prior art arrangements. The new arrangement herein disclosed comprises a means common to the trunk line, that is, a means located in the cord circuit. More 50 specifically, the time counting arrangement is common to the cord circuits that are, in turn, common to the trunks, so that a great

economy and a corresponding simplicity in the circuits have been achieved.

In accordance with another feature of this 55 invention means for applying ringing current to the trunk line is made to operate automatically and in response to the setting of a switch over the trunk line. When the connector has been set on the terminals of 60 the called line, current in the trunk line is reversed and a polarized relay in the dialing circuit common to the cord circuits is operated and this, in turn, causes the energization of a ringing start relay which is 65 limited in the duration of the time of its operation by a set of time counting relays also set in operation by the polarized relay.

In accordance with still another feature 70 there is provided a means for listening and talking on a second cord circuit by operating a listening key on such second cord circuit. Under ordinary conditions the operation of a listening key cuts off the operator's transmitter and leaves only the operator's receiver in connection with the cord circuit. 75 Also under ordinary conditions the operation of a talking key exclusively associates considerable common apparatus with the cord circuit so that if while the operator 80 is using a certain cord circuit a connection on another cord circuit requires attention, it would be impossible to give such attention without entirely abandoning the operations of the first cord circuit. A monitoring cut-off relay is therefore provided so 85 that by operating the listening key of a second cord circuit the operator may talk over a second cord circuit without either cutting off the transmitter or disturbing the common apparatus now connected to the first cord circuit.

In the drawings a telephone system embodying among others the above described features is shown in diagrammatic form. 95 In Fig. 1 there is shown a cord circuit and certain of the circuits and apparatus common thereto. In Fig. 2 there is shown the remainder of the circuits and apparatus common to the cord circuit of Fig. 1. In Fig. 3 there is shown a repeated dialing trunk and in Fig. 4 there is shown a loop dialing trunk both adapted to cooperate 100 with the cord circuit of Fig. 1.

When the operator wishes to establish a connection over the repeated dialing trunk shown in Fig. 3 she inserts plug 104 in jack 301. She then operates the talking key T 5 individual to the cord circuit and the front dialing key 203 common to the cord circuit whereupon a circuit is established from ground, left hand high resistance winding 10 of sleeve relay 302, sleeve of jack 301, sleeve 15 of plug 104 through the 6th and 7th springs of key T (counting from the bottom), conductor 107, lower contacts of the front dial release key 201, conductor 108, winding of marginal relay 109, winding of relay 110 to battery and ground. Relay 110 and relay 302 become actuated in this circuit, but relay 109 does not operate due to the 20 resistance of this circuit. It will later be shown how this resistance is lowered by a parallel circuit through the right hand low resistance winding of relay 302 whereupon relay 109 will operate. Through the actuation of key T a circuit is established from battery, right hand winding of relay 103, 25 the 13th and 14th contact springs of key T, conductor 112, and the normal contact of relay 111 to ground. Relay 103 becomes energized in this circuit and establishes a connection through its outer right hand armature and front contact and conductor 118 for the energization of relay 111. Relay 111 now transfers the ground connection from conductor 112 to conductor 113 whereupon ground is extended through the 11th 30 and 12th springs of key T to the inner left hand armature and front contact of relay 103, thence through the left hand winding of relay 103 to battery to hold this relay locked so that as long as the key T is in its 35 operated position relay 103 individual to the cord circuit and relay 111, common to the cord circuit are operated. Relay 103 splits the cord and associates the group of conductors 114 with the cord circuit.

Upon the operation of relay 110 a circuit is established from ground, armature and front contact of relay 110, winding of relay 202 to battery and ground. Relay 202 becomes operated and extends the ground on conductor 113 through the back contact and outer right hand armature of relay 205, the lower contacts of front dialing key 203, the lowermost armature and front contact of relay 202, conductor 115 to the winding of relay 116, common to the cord circuits. Relay 116 operates in this circuit. The ground on conductor 113 is also extended through the outer left hand armature and back contact of relay 121, the normal contacts of relay 206, armature and back contact of polarized relay 120, front contact and outer right hand armature of relay 116, conductor 122, upper contacts of front dial release key 201, normal contacts of the left hand armature of relay 207, winding of relay 45

125 to ground. Relay 125 becomes operated in this circuit and by attracting its armature establishes an obvious circuit for relay 207. Relay 207 now locks in to the ground provided for the energization of relay 125 and 50 relay 125 remains operated in a circuit extending from battery, winding of relay 125, winding of marginal relay 126, front contact and right hand armature of relay 125, back contact and left hand armature of relay 208, normal contacts of the inner left hand armature of relay 121, inner left hand armature and alternate contact of relay 116, front contact and outer left hand armature of relay 103, normal lower contacts of front 55 ringing key 119, tip of plug 104, tip of jack 301, upper armature and back contact of relay 303, winding of relay 304 to ground. Relay 304 being of low resistance causes the operation of relay 126 as well as the operation of relays 125 and 304. Thereupon a circuit is closed from ground, armature and front contact of relay 126, normal contacts of the outer right hand armature of relay 121, winding of relay 209 to battery and ground. Relay 209, known as the repeated 60 dialing relay now establishes a circuit from battery through resistance 128, front contact and left hand armature of relay 209, contacts of dial 129, winding of polarized relay 120, inner right hand armature and alternate contact of relay 116, front contact and inner right hand armature of relay 103, ring of plug 104, ring of jack 301, lower armature and back contact of relay 303, winding of 65 relay 305, to ground, resulting in the energization of relay 305.

Upon the operation of relay 209 a circuit is established from ground, the upper contacts of front dialing key 203, right hand armature, and front contact of relay 209, winding of relay 121 to battery. Relay 121 becoming energized establishes a substitute circuit for relay 209 extending from ground, outer right hand armature and front contact 70 of relay 121, through the winding of relay 209 to battery and ground. Relay 121 also provides a locking circuit for relay 116 over its inner right hand armature and front contact. Relay 121 now substitutes battery 75 through resistance 130 in place of battery through the windings of relays 125 and 126 and these latter relays become deenergized. Relay 121 also opens the circuit of relay 207 and this relay releases. The circuit through 80 the left hand armature and back contact of relay 125, right hand armature and front contact of relay 207, winding of relay 210 to battery and ground is not effectively established at this time since the deenergization of relays 125 and 207 is controlled by relay 121. Since relay 207 is controlled by a simple back contact of relay 121, relay 207 will open its right hand contact before relay 125 can close its left hand back contact. 85

With relays 304 and 305 energized, a circuit is established from ground on conductor 306 through the armature and back contact of relay 307, winding of relay 308, inner 5 right hand armature and back contact of relay 309, winding of polarized relay 310, armature and front contact of relay 305, right hand armature and front contact of relay 304, conductor 311, resistance 312, back 10 contact and lower armature of relay 307, to battery on conductor 313. Conductors 306 and 313 extend to an automatic switch such for instance as that shown in Fig. 3 of Patent No. 1,474,008 to Stokely and as there 15 shown are connected through the windings of the line relay to ground and battery respectively. Thus a bridge for the energization of the distant selector line relay is established. Relay 308 is energized in this 20 bridge circuit.

The energization of relay 304 opens the circuit of relay 303 so that it cannot operate at this time. The energization of relay 304 also establishes a circuit from battery, left 25 hand armature and back contact of relay 309, resistance 314, front contact and inner left hand armature of relay 304, back contact and right hand armature of relay 315, winding of relay 316 to ground. Relay 316 being 30 comes energized and closes a circuit from ground, the right hand armature and front contact of relay 302, the front contact and inner left hand armature of relay 316 through the winding of relay 315 to battery 35 and ground and relay 315 through its front contact and left hand armature locks to the ground supplied by the right hand armature of relay 302. The original energizing circuit of relay 316 is now opened but 40 an alternate circuit is provided so that relay 316 remains energized in a circuit from battery, left hand armature and back contact of relay 309, resistance 314, front contact and right hand armature of relay 315, winding 45 of relay 316 to ground.

The dialing circuit is now complete, relay 305 being energized in series with the dial 129 and resistance 128 to battery. The operator will actuate dial 129 to send out an 50 appropriate number of trains of impulses which each in the form of a series of short interruptions of the circuit through relay 305. Relay 305 responds to each impulse by opening its contact. This, in turn, opens the 55 bridge across the trunk leading from the right hand portion of Fig. 3 and thus operates the line relay in the distant selector circuit to set up a connection in the manner fully explained in the Stokely Patent 1,474-, 60 008 hereinbefore referred to. Relay 308 in this bridge circuit responds to each impulse by closing its armature and contact and this in turn completes a short circuit about the winding of relay 316, the circuit extending 65 from the armature and back contact of relay 308, the inner left hand armature and front contact of relay 304, the front contact and right hand armature of relay 315 to the winding of relay 316. The period of each of these short-circuits, however, is very 70 small and relay 316 being slow to release does not respond by returning to normal but, on the other hand, remains in its operated position.

If, during the dialing period an "all terminals busy" condition is encountered the talking circuit is opened momentarily. This causes relay 308 to become deenergized for a period longer than the duration of an impulse and thereupon relay 316 becomes deenergized through having its winding short circuited. Upon the deenergization of relay 316, a circuit is established from ground, right hand armature and front contact of relay 302, left hand armature and front 85 contact of relay 315, inner left hand armature and back contact of relay 316, winding of relay 309 to battery and ground. Relay 309 becomes energized and permanently opens the bridge across the outgoing end of the trunk. Relay 309 also closes a circuit from ground, interrupter 317, front contact and outer right hand armature of relay 309, back contact and right hand armature of relay 316, back contact and outermost lower 90 armature of relay 318, back contact and right armature of relay 319, right hand low resistance winding of relay 302, sleeve of jack 301, sleeve of plug 104, 6th and 7th contact springs of key T, conductor 107, lower 95 contact springs of dial release key 201, windings of marginal relay 109 and relay 110 to battery and ground. Since the resistance of the original circuit through relays 109 and 110 is now lowered by this parallel circuit through the right hand winding of relay 302, the marginal relay 109 will become 100 energized. The energization of marginal relay 109 will be periodic, following the impulses set up through the interrupter 317. 105 During the period when relay 109 is deenergized a circuit is established from battery, lamp 124, the 3rd and 4th contact springs of key T, conductor 117, high resistance 110 127, front contact and inner upper armature of relay 202 to ground. Due to the resistance 127, lamp 124 does not become sufficiently illuminated to be visible. During the periods when relay 109 is operated, resistance 127 is shunted by low resistance 131 and this so increases the current flow in lamp 124 that it becomes illuminated, and thus lamp 124 flashes in unison with the interrupter 317. It should be noted that the circuit through resistance 131 leads 115 through the front contact of relay 109 and thence through the back contact and right hand armature of relay 209. Since this latter relay is energized as long as dialing key 203 is actuated the above described flashing 120 125 130

circuit will be ineffective. As soon, however, as key 203 is returned to normal relays 121 and 209 will return to normal and lamp 124 will begin to flash.

- 5 Should the talking key T be released at this time, the circuit for flashing lamp 124 would extend over the sleeve of plug 104 through the 5th and 7th contact springs of key T directly to the lamp 124 so that the alternate establishment of a ground path in parallel with the left hand winding of relay 302 would accomplish the same result with regard to lamp 124 as the shunting of resistance 127 by resistance 131.
- 15 Should the called line prove to be busy, relay 316 remains in its operated position, and interrupter 320, designed to transmit impulses at a higher rate, will operate over the circuit just described for interrupter 317
- 20 so that the lamp 124 will flash at a correspondingly higher rate. The circuit for interrupter 320 of course, is established as soon as the dialing circuit is completed but the lamp 124 is prevented from giving the busy
- 25 indication as long as the dialing key is operated, as above described. The operator, however, would have no occasion to release the dialing key until she had completed the dialing operation so there is no danger that
- 30 the busy signal which could be made to operate before the called line were even seized would be mistaken.

- In case the called line proves to be idle, then the circuit for interrupter 320 is opened immediately after the last series of impulses has been sent. This is accomplished by the reversal of the current flow in the trunk by the connector in the well known manner and the consequent operation of polarized relay

- 40 310.
- Upon the operation of polarized relay 310, an obvious circuit for relay 318 is closed, whereupon this relay becomes energized, locks up under control of relay 302, and connects the repeating coil 321 to the trunk conductors leading to the right of Fig. 3. Relay 319 is now bridged across the trunk and will become energized by the battery supplied from the connector. Upon its energization, relay 319 closes a circuit from ground, front contact and right hand armature of relay 319, through the right hand low resistance winding of relay 302 to cause the operation of marginal relay 109 and to in turn cause the illumination of lamp 124 as a signal that the called line has been seized. A circuit is also closed from ground, right hand armature and front contact of relay 302, armature 322 and front contact of relay 318, winding of relay 309, to battery and ground whereupon relay 309 attracts its armatures and opens the bridge including the windings of relays 308 and 310. At its left hand armature, relay 309 also opens the circuit of relay
- 55 316 so that this relay now becomes deener-

gized. Relay 315, however, is maintained energized under control of relay 302.

The operator will now release dialing key 203 whereupon relays 116, 121 and 209 are released. Upon the release of relay 116 the energizing circuit for relay 304 is open and relay 304 in restoring its armatures to normal establishes a circuit from ground, right hand armature and front contact of relay 302, front contact and the second lower armature of relay 318, the back contact and outer left hand armature of relay 304, winding of relay 303 to battery and ground. Relay 303 now becomes energized and connects the tip and ring conductors from jack 301 to the windings of repeating coil 321. A talking circuit may now be traced from the lower left hand winding of repeating coil 321, front contact and lower armature of relay 303, ring conductor of jack 301, ring conductor of plug 104, inner right hand armature and front contact of relay 103, normal contacts of the inner right hand armature of relay 116, lower contacts of the front splitting key 212, inner lower armature and front contact of relay 202, conductor 213, winding of induction coil 215, conductor 216, front contact and upper outer armature of relay 202, upper contacts of front splitting key 212, normal contacts of the outer left hand armature of relay 116, front contact and outer left hand armature of relay 103, lower normal contacts of front ringing key 119, tip of plug 104, tip of jack 301, upper armature and front contact of relay 303, and upper left hand winding of repeating coil 321. The operator's telephone set designated in general by the numeral 217 is associated with the windings of induction coil 215 and hence the operator may communicate over the trunk circuit while the circuits are in this condition. As soon as the operator is ready, she will actuate the trunk ringing key 119 whereupon a circuit is established from battery, resistance 218, conductor 132, front contact of the lower contact set of front ringing key 119, tip of plug 104, tip of jack 301, upper armature and front contact of relay 303, upper left hand winding of repeating coil 321, winding of ringing relay 307, to ground. Relay 307 becomes actuated in this circuit and applies ringing current to the conductors of the trunk leading to the called party's telephone. When the called party answers, current will be disconnected from the trunk in the manner explained in the patent to Stokely No. 1,474,008 and relay 319 will become deenergized. Upon the deenergization of this relay, the low resistance circuit through the right hand winding of relay 302 will be opened and relay 109 will become deenergized thus causing signal lamp 124 to become darkened as a signal that the called party has answered. The operator may now converse with the called party over the talk-

80 85 90 95 100 105 110 115 120 125 130

- ing circuit above described and when the connection through the rear plug 133 is properly established, the operator will restore her talking key T to normal leaving a clear path 5 between the calling and called parties. Such a clear path may be traced from the ring of plug 133, through the back contact and right hand armature of relay 103 to the ring of plug 104 and from the tip of plug 133 10 through the normal upper contacts of rear ringing key 134, the back contact of the outer left hand armature of relay 103, normal lower contacts of front ringing key 119 to the tip of plug 104. When the conversation has ceased and the called party replaces his receiver on its hook, current will again be applied to the repeated dialing trunk and relay 319 will become energized, whereupon the circuit through the low resistance right 15 hand winding of relay 302 will be closed and the signal lamp 124 will become illuminated as a disconnect signal.

When the operator wishes to establish a connection over either of the trunks shown 20 in Figs. 3 or 4, she first touches the tip of plug 104 to the sleeve of either jack 301 or 401. Under the idle condition ground potential is placed on the sleeve of the jack but when the trunk is busy battery potential 25 will be found at this point and a circuit will be established from battery, tip of plug 104, the normal contacts of the lower set of front ringing key 119, outer left hand armature and front contact of relay 103, normal contacts of the outer left hand armature of relay 116, upper contacts of front splitting key 212, upper outer armature and back contact of relay 202, right hand winding of repeating coil 214 to ground. Repeating coil 30 214 induces in the secondary winding an impulse of current which will travel from the lower terminal of the left hand winding of repeating coil 214, back contact and inner upper armature of relay 221 through the operator's receiver, the inner lower armature and back contact of relay 221, the condenser 35 222 to the upper terminal of the upper left hand winding of repeating coil 214. This impulse will cause a click in the receiver and will be taken by the operator as a busy indication.

When the operator wishes to establish a connection over the loop dialing trunk shown 40 in Fig. 4 she inserts plug 104 into jack 401. She then operates the talking key T and the front dialing key 203 as before. A circuit is now established from ground, left hand high resistance winding of sleeve relay 402, sleeve of jack 401, sleeve of plug 104 45 through the 6th and 7th contact springs (counting from the bottom) of key T conductor 107, lower contacts of front dial release key 201, conductor 108, winding of marginal relay 109, winding of relay 110 to

battery and ground. Relay 110 and relay 402 become actuated in this circuit but relay 109 does not operate due to the high resistance of the left hand winding of relay 402. Relay 103 becomes energized in the manner hereinbefore described and causes in turn the 50 energization of relay 111. Relay 111 in turn places ground on conductor 113.

Upon the operation of relay 110 a circuit is established from ground, armature and front contact of relay 110, winding of relay 202 to battery and ground. Relay 202 becomes operated and extends the ground on conductor 113 through the back contact and outer right hand armature of relay 205 and lower contacts of front dialing key 203, the 55 lowermost armature and front contact of relay 202, conductor 115 to the winding of relay 116 which thereupon becomes operated. The ground on the conductor 113 is also extended through the outer left hand armature and back contact of relay 121, the normal contacts of relay 206, armature and back contact of polarized relay 120, front contact and outer right hand armature of relay 116, conductor 122, upper contacts of front dial 60 release key 201, normal contacts of the left hand armature of relay 207, winding of relay 125 to ground. Relay 125 becomes operated in this circuit and by attracting its armature establishes an obvious circuit for 65 relay 207. Relay 207 now locks into the ground providing for the energization of relay 125 and relay 125 remains operated in a circuit extending from battery, winding of relay 125, winding of marginal relay 126, 70 front contact and right hand armature of relay 125, back contact and left hand armature of relay 208, normal contacts of the inner left hand armature of relay 121, inner left hand armature and contact of relay 116, 75 front contact of outer left hand armature of relay 103, normal lower contacts of front ringing key 119, tip of plug 104, tip of jack 401, upper armature and back contacts of relay 403, winding of relay 403 to ground. Relay 403 operates in this circuit and locks 80 in a circuit including battery, the right hand armature and front contact of relay 402, the alternate contacts of the upper armature of relay 403, winding of relay 403 to ground. 85 Due to the relatively high resistance of relay 403, marginal relay 126 does not become operated prior to the operation of relay 403 and upon the operation of relay 403 the circuit of relays 125 and 126 becoming open 90 causes the deenergization of both these relays. Since relay 126 fails to operate at this time, neither relays 209, nor 121 become operated. Upon the release of relay 125 a connection is extended from ground, the left hand armature and back contact of relay 125, right hand armature and front contact 95 of relay 207, winding of relay 210 to battery 100

105

110

115

120

125

and ground. Relay 210 becoming operated closes a circuit through the normal contacts of relay 219 to the winding of relay 211, which now becomes operated. Upon the operation of relay 211 a circuit is closed from ground, inner left hand armature and front contact of relay 211, winding of relay 205 to battery and ground and relay 205 locks through its inner left hand armature to the ground supplied by the upper contact of dialing key 203. Relay 205 opens at its outer right hand armature, the circuit extending through the lower contacts of dialing key 203, the lower outer armature and front contact of relay 202, conductor 115 to the winding of relay 116 so that the original energizing circuit of this latter relay is opened. However, relay 116 remains energized in a circuit controlled by the right hand armature and front contact of relay 211.

The dialing circuit is now complete and may be traced from conductor 404, the upper armature and back contact of relay 407, the normal contacts of the upper armature of relay 405, the front contact and upper armature of relay 403, tip of jack 401, tip of plug 104, the normal lower contacts of front ringing key 119, front contact and outer left hand armature of relay 103, alternate contact and outer left hand armature of relay 116, normal contacts of inner left hand armature of relay 121, left hand armature and front contact of relay 208, normal contacts of the right hand armature of relay 125, back contacts and left hand armature of relay 209, dial 129, winding of polarized relay 120, inner right hand armature and alternate contact of relay 116, alternate contact and inner right hand armature of relay 103, ring of plug 104, ring of jack 401, lower armature and front contact of relay 403, inner lower armature and back contact of relay 405, winding of polarized relay 410, back contact and lower armature of relay 407 to conductor 406. Conductors 404 and 406 lead to a toll switching trunk such for instance as that shown in Fig. 3 of Patent No. 1,543,685 to Stokely. As explained in such patent ground and battery are connected to these conductors through the line relay of a selector switch so that current now flows over the circuit described to operate such distant line relay but flows in such a direction that neither polarized relay 410 nor polarized relay 120 is energized. The operator may now dial the designation of the called party whereupon the switches in the toll train will be actuated in the manner fully explained in the patent to Stokely No. 1,543,685.

When the called line is seized the current flow in the dialing circuit is reversed and both relays 410 and 120 become energized. Upon the energization of relay 410 a circuit is established from battery, armature and

front contact of relay 410, lower outer armature, and of relay 405, winding of relay 405, to ground. Relay 405 becomes energized and locks to the battery supplied by the right hand armature of relay 402, whereupon relay 410 becomes ineffective to cause any further change in this trunk circuit. 70

The operation of relay 120 establishes a circuit from battery, winding of relay 206, front contact and armature of relay 120, normal contacts of the right hand armature of relay 206, back contact and outer left hand armature of relay 121, conductor 113, armature and front contact of relay 111 to ground, causing the energization of relay 206. Relay 206 now locks in a circuit from battery, winding of relay 206, outer left hand armature and front contact of relay 211, right hand armature and front contact of relay 206, and thence over the circuit just described to the ground on conductor 113 supplied by the energization of relay 111. Relay 206 in energizing establishes a circuit from ground, left hand armature and front contact of relay 206, contacts of key 220, winding of relay 208 to battery and ground. Relay 208 becomes energized and opens the dialing circuit at its left hand armature. Through its right hand armature, relay 208 closes a circuit from ground, armature and front contact of relay 210, front contact and right hand armature of relay 208, winding of relay 219, to battery. Relay 219 becoming energized opens the original energizing circuit for relay 211 but substitutes therefor a circuit from its own armature to the winding of relay 211. 85

Relay 208 is provided to automatically start ringing on the toll switching trunk. This is accomplished by the establishment of a circuit from battery, resistance 218, front contact and left hand armature of relay 208, normal contacts of the inner left hand armature of relay 121, outer left hand armature and alternate contacts of relay 116, alternate contact and outer left hand armature of relay 103, normal lower contacts of front ringing key 119, tip of plug 104, tip of jack 401, upper armature and front contact of relay 403, upper armature and front contact of relay 405, upper left hand winding of repeating coil 421, winding of relay 407 to ground. Relay 407 applies ringing current to the conductors 404 and 406 to call the called party in the manner fully described 105 in the Stokely patent above referred to. 110

Upon the operation of relay 120 as above described the holding circuit of relay 207 which was traced through the back contact of polarized relay 120 is opened and this 115 relay becoming deenergized opens the circuit of relay 210. Relay 210, however, is slow to release and so holds over for an instant after relays 206, 208 and 219 have become operated and relay 219 being also slow to 125 130

release holds for an additional period of time after relay 210 releases its armature. Therefore after relay 208 has become energized time is counted by relays 210 and 219 to hold relay 211 operated for a predetermined period. At the end of this period relay 211 releases and in so releasing opens the circuit of relay 116 which thereupon returns to normal and opens the ringing circuit established by relay 208. The release of relay 211 opens the holding circuit of relay 206 and this relay returns to normal. Relay 120 having returned to normal upon the energization of relay 208 there is no circuit to maintain relay 206 energized, thus relay 407 is energized only for a predetermined length of time.

It has been stated that under normal conditions current through the windings of the line relay of the distant selector switch flows through conductors 404 and 406. Upon the seizure of the called line this current flow is reversed causing the operation of relay 410 and 405. The operation of relay 405 closes the circuit for the upper right hand winding of repeating coil 421 so that relay 419 is now placed in series with the windings of the line relay of the distant selector switch and relay 419 thereby becomes operated. Relay 419 of the loop dialing trunk performs the same function as relay 319 of the repeated dialing trunk, that is, closes a circuit through the right hand low resistance winding of relay 402 and this in turn causes the operation of the supervisory lamp 124.

When the called party answers current is removed from the conductors 404 and 406 and relay 419 returns to normal. In doing so relay 419 opens the circuit through the right hand low resistance winding of relay 402 and causes the supervisory lamp 124 to become dark as an indication to the operator that a called party has answered.

At the end of the conversation the called party in replacing his receiver on its hook again causes the energization of relay 419 and thus closing the circuit through the right hand low resistance winding of relay 402 causes the illumination of supervisory lamp 124 as an indication to the operator that the conversation has ceased. She thereupon removes plug 104 from jack 401 and by releasing relay 402 causes the loop dialing trunk relays to return to normal.

The circuit for energizing the automatic ringing start relay 208 was traced through the contacts of key 202. This key is provided for night service operation where it is not desired to start ringing automatically. With key 220 actuated, then upon the operation of relay 206, relay 208 does not become operated. Under these conditions, relay 419 becoming operated closes a circuit through the left hand low resistance winding of relay 402 to cause the operation of super-

visory lamp 124. This notifies the operator that the called party's line has been seized and when the operator is ready she will actuate front ringing key 119. Thereupon a circuit will be extended from battery, resistance 218, conductor 132, alternate contacts of the lower contact set of front ringing key 119, tip of plug 104, tip of jack 401, upper armature and front contact of relay 403, upper armature and front contact of relay 405, upper left hand winding of repeating coil 421, winding of relay 407 to battery and ground. Relay 407 becoming operated applies ringing current to the conductors 404 and 406 to cause the ringing of the called party's telephone.

Under the conditions hereinbefore described, in relation to the operation of the automatic ringing start relay 208, it was noted that relays 210 and 219 counted time for the application of ringing current to the trunk line for a definite period of time. If the called line when seized were busy, the application of ringing current would have no effect and since relay 407 is only operated for a short and definite period of time, the trunk line will shortly revert to the condition in which it would be found if the ringing relay 407 had not been operated. Under this condition and as described in the patent to Stokely No. 1,543,685, relay 419 would be periodically energized and deenergized and this in turn would cause the periodic operation of supervisory lamp 124 to notify the operator that the called line is at this time busy.

It may be mentioned here, in passing, that both relays 319 and 419 are provided with a left hand armature to which battery is connected upon its operation. This connection plays no part in the present invention being provided for causing the supervisory operation in connection with a different type cord circuit than that shown in Fig. 1.

During the time when the cord circuit shown in the upper part of Fig. 1 is in use, the operator may monitor on the cord by actuating key M. The operation of this key closes a circuit from ground, the lower set of contacts of key M, through the back contact and outer right hand armature of relay 204, winding of relay 221 to battery and ground. The operation of relay 221 connects the left hand winding of repeating coil 224 to the operator's receiver. The upper and middle set of contact springs of the key M connects the tip and ring conductors of the cord circuit through the condenser 223 to the right hand windings of repeating coil 224 and in this manner the operator may listen to any conversation going on over the cord circuit, but cannot talk, since the transmitter circuit is cut off by the operation of relay 221.

It should be noted that when the key T

is actuated and relay 111 becomes operated the ground for operating relay 111 also closes the circuit for the operation of the monitoring cut-off relay 204 and connects the monitoring leads from the key M to the windings of repeating coil 215. This feature is provided so that, while the operator has her common apparatus such as the supervisory control relays 109 and 110 for the front 5 cord and the corresponding relays for the rear cord, together with the different keys such as the splitting key, the dial release key and the dialing key and the common dialing circuit connected to one cord, she may talk 10 over another cord by merely throwing the monitoring key of such other cord. There are occasions when such operation is desirable as when, for instance, the operator is in the act of establishing a connection over one 15 cord and is waiting for the called subscriber to answer. At such a time another connection on another cord may require attention and this can now be given by operating the monitoring key of such other cord circuit. 20 25 The dial release key 201 is provided for releasing the dialing circuit under certain conditions. It will be noted that when the plug 104 has been inserted in a loop dialing trunk such as that shown in Fig. 4 that relay 211 becomes operated. Relay 211 in operating establishes a connection from ground, the alternate contacts of the inner left hand armature of relay 211 to the holding circuit 30 for relay 103, so that even though the operator releases her talking key T she may not restore the common apparatus including the dialing circuit to normal. If it is found necessary to do this, the operator will then depress the dial release key 201 which by opening its upper contacts will release relay 207 35 with the effect hereinbefore described.

Resistance 135 and condenser 136 comprise a balancing network which may be connected to the rear cord when the front 40 ringing key 119 is operated. This balancing network performs the function of balancing toll lines which may have repeaters connected thereto, in order to prevent singing. The balancing network is also associated 45 with the rear ringing key 134 so as to balance a toll line which may be connected to the front cord when the rear ringing key 134 is 50 operated.

What is claimed is:

1. In a telephone system, a cord circuit for extending connections to trunk lines, trunk lines of different character, automatic switches operable over said trunk lines, a switch controlling circuit associated with said cord circuit, and means in said controlling circuit for automatically adapting said controlling circuit to said different character trunk lines.
2. In a telephone system, a cord circuit for extending connections to trunk lines, trunk lines of one character having a low resistance 55 lines of one character having a low resistance

tip circuit, trunk lines of another character having a high resistance tip circuit, automatic switches operable over said trunk lines, a switch controlling circuit associated with said cord circuit, and a marginal relay arrangement in said controlling circuit for adapting said controlling circuit to said different character trunk lines.

3. In a telephone system, a cord circuit for extending connections to trunk lines, trunk lines of different character, said trunk lines and said cord circuit having a single character of supervisory means in their sleeve circuits, automatic switches operable over said trunk lines, a switch controlling circuit associated with said cord circuit, and means in said controlling circuit for automatically adapting said controlling circuit to said different character trunk lines.

4. In a telephone system, a cord circuit for extending connections to trunk lines, trunk lines of one character having a low resistance tip circuit, trunk lines of another character having a high resistance tip circuit, said trunk lines and said cord circuit having a single character of supervisory means in their sleeve circuits, automatic switches operable over said trunk lines, a switch controlling circuit associated with said cord circuit, and a marginal relay arrangement in said controlling circuit for adapting said controlling circuit to said different character trunk lines.

5. In a telephone system, a cord circuit for extending connections to trunk lines, trunk lines of different character, automatic switches operable over said trunk lines, a switch controlling circuit normally disconnected from said cord circuit, means for temporarily connecting said controlling circuit to said cord circuit, and means in said controlling circuit for automatically adapting said controlling circuit to said different character trunk lines.

6. In a telephone system, a cord circuit for extending connections to trunk lines, trunk lines of one character having a low resistance tip circuit, trunk lines of another character having a high resistance tip circuit, automatic switches operable over said trunk lines, a switch controlling circuit normally disconnected from said cord circuit, means for temporarily connecting said controlling circuit to said cord circuit, and a marginal relay arrangement in said controlling circuit for adapting said controlling circuit to said different character trunk lines.

7. In a telephone system, a cord circuit for extending connections to trunk lines, trunk lines of one character having a low resistance tip circuit, trunk lines of another character having a high resistance tip circuit, said trunk lines and said cord circuit having a single type of supervisory means in their sleeve circuits, automatic switches operable

- over said trunk lines, a switch controlling circuit normally disconnected from said cord circuit, means for temporarily connecting said controlling circuit to said cord circuit, 5 and a marginal relay arrangement in said controlling circuit differentially responsive to said low resistance tip circuit and said high resistance tip circuit for adapting said controlling circuit to said different character 10 trunk lines.
8. In a telephone system, a cord circuit for extending connections to trunk lines, trunk lines of different character, automatic switches operable over said trunk lines, a switch controlling circuit common to said cord circuit, and means in said controlling circuit for automatically adapting said controlling circuit to said different character trunk lines.
9. In a telephone system, a cord circuit for 20 extending connections to trunk lines, trunk lines of one character having a low resistance tip circuit, trunk lines of another character having a high resistance tip circuit, automatic switches operable over said trunk lines, a switch controlling circuit common to said cord circuit, and a marginal relay arrangement in said controlling circuit differently responsive to said low resistance tip circuit and said high resistance tip circuit for adapting said controlling circuit to said different character trunk lines.
10. In a telephone system, a cord circuit comprising in normal condition a clear pair of conductors only for a talking circuit and 25 a third conductor including supervisory means, trunk lines of different character accessible to said cord circuit, automatic switches operable over said trunk lines, a switch controlling circuit for association with said cord circuit, and means in said controlling circuit for automatically adapting said controlling circuit to said different character trunk lines.
11. In a telephone system, a cord circuit comprising in normal condition a clear pair 30 of conductors only for a talking circuit and a third conductor including supervisory means, trunk lines of one character having a low resistance tip circuit, trunk lines of another character having a high resistance tip circuit, automatic switches operable over said trunk lines, a switch controlling circuit for association with said cord circuit, and a marginal relay arrangement in said controlling circuit selectively responsive to said low resistance tip circuit and said high resistance tip circuit for adapting said controlling circuit to said different character trunk lines.
12. In a telephone system, a cord circuit, 35 a trunk line accessible to said cord circuit, automatic switches operable over said trunk line, a switch controlling circuit common to said cord circuit, a polarized relay in said controlling circuit responsive to the setting 65 of a switch, a relay responsive to said polarized relay for applying ringing current to said trunk line, and a plurality of relays for counting time for limiting the energization of said last relay to a predetermined 70 period of time.
13. In a telephone system, a cord circuit, a trunk line accessible to said cord circuit, a ringing relay in said trunk line for applying ringing current to said trunk, automatic switches operable over said trunk line, a switch controlling circuit common to said cord circuit, a polarized relay in said controlling circuit responsive to the setting of a switch, a relay responsive to said polarized relay for operating said ringing relay, and a plurality of relays for counting time for 75 limiting the energization of said last relay to a predetermined period of time.
14. In a telephone system, cord circuits 80 each including an individual listening key and an individual talking key, control circuits and apparatus including an operator's transmitter and receiver common to said cord circuits, means responsive to the actuation of a listening key, for associating said operator's receiver only with the corresponding cord circuit, means responsive to the actuation of a talking key for exclusively associating said common circuits and 85 apparatus with the corresponding cord circuit, and means responsive to the actuation of a listening key of one cord circuit during the operation of a talking key of another cord circuit for associating both the said 90 transmitter and the said receiver with the said one cord circuit.
15. In a telephone system, cord circuits 95 each including an individual listening key and an individual talking key, controlling circuits and apparatus including an operator's transmitter and receiver common to said cord circuits, means responsive to the actuation of a listening key for associating said operator's receiver with the corresponding cord circuit, a relay responsive to the said actuation of said listening key for cutting off the said operator's transmitter, means responsive to the actuation of a talking key for exclusively associating said common circuits and apparatus with the corresponding cord circuit and means responsive to the actuation of a listening key of one cord circuit during the operation of a talking key of another cord circuit for associating both the said transmitter and the said receiver with the said one cord circuit.
16. In a telephone system, cord circuits 105 each including an individual listening key and an individual talking key, controlling circuits and apparatus including an operator's transmitter and receiver common to said cord circuits, means responsive to the 110

actuation of a listening key for connecting said operator's receiver to the corresponding cord circuit, a relay responsive to the said actuation of the said listening key for cutting off the said operator's transmitter and means responsive to the actuation of a talking key for exclusively associating said com-

mon circuits and apparatus with the corresponding cord circuit, said last means including a relay for rendering ineffective 10 said first relay.

In witness whereof, I hereunto subscribe my name this 24 day of May, A. D. 1927.

LESLIE F. PORTER.
